UNITED STATES PATENT OFFICE.

WALTER C. FELLOWS, OF PHILADELPHIA, PENNSYLVANIA, ASSIGNOR TO KELLER MANUFACTURING COMPANY, OF PHILADELPHIA, PENNSYLVANIA, A CORPORATION OF DELAWARE.

ELECTRICAL ATTACHMENT-PLUG.

1,009,659.

Specification of Letters Patent. ~ Patented Nov. 21, 1911.

Application filed December 22, 1910. Serial No. 598,679.

To all whom it may concern:

Be it known that I, WALTER C. FELLOWS, of Philadelphia, in the county of Philadelphia and State of Pennsylvania, have invented certain new and useful Improvements in Electrical Attachment-Plugs, whereof the following is a specification, reference being had to the accompanying drawings.

My invention relates to an attachment 10 plug, such as may be used at the end of a flexible lead for the purpose of plugging into a pocket and has reference to the means employed for so securing the end of the lead to the plug as to avoid imposing strain upon 15 either the wires of the lead or their connections within the plug.

In the accompanying drawings, Figure I, is a plan view, and Fig. II, a side view of a 20 plug embodying my invention. Fig. III, is a horizontal sectional view, the upper half of the plug being removed. Figs. IV, and V, are detail perspective views of parts hereinafter described.

The plug 1, is formed of insulating material and is properly shaped to snugly fit the 25 socket for which it is designed. It consists of half portions 2, 2, united by screws 3, 3.

The inner faces of the half portions are 30 suitably cut away to accommodate the metal strips 4, 4, the binding screws 5, 5, and the locking contact points on springs 6, 6, the latter being in proper relation to guide holes 7, 7, through which suitable contact points may be caused to pass into electrical 35 engagement with the locking springs, as well understood in the art.

At the end of the plug to which the lead is to be secured, an attachment piece in the 40 form of a ring 10, (most clearly shown in Fig. V), is provided. In order to firmly secure this ring to the plug, I prefer to make it of metal, and cast integrally with it two plates or lugs 11, 11, which rest within corresponding recesses between the half portions of the plug to which it is attached, by screws 12, 12, passing through both the plug and said plates.

The interior of the ring 10, is coned so as 45 to diminish in diameter toward the end farthest from the plug. This coned interior receives a conical split bushing 15, the outer surface of which is coned in correspondence with the interior surface of the ring 10. The

bushing may be made of fiber or other suitable material. It is split so as to give it 55 capacity for expansion and contraction, and may conveniently be split at two points as shown in Fig. IV. The bushing is internally roughened as by providing it with a screw thread or with corrugations. The internal diameter of the bushing is such as to tightly receive the end of a twin lead 20, which is to be attached to the plug. The wires from the end of the twin lead pass to their respective binding screws with sufficient slack to prevent direct pull thereon.

When the bushing is inserted within its conical socket in the ring 20, the pressure upon the split bushing forces it to tightly grip the end of the twin lead, and owing to 70 the engagement of the conical surfaces of the bushing 15, and the ring 10, any pull upon the twin lead causes the bushing to the more tightly grip the lead so as to preclude the possibility of the lead being so far 75 pulled from its grasp as to allow the individual wires of the lead or their connections to receive any of the strain.

Having thus described my invention, I claim:—

1. An electrical plug formed in two parts secured together face to face and provided with recesses for the electrical connections, an attachment piece having a tapered opening communicating with the interior of the 85 plug, and provided with attaching devices extending between the meeting faces of the plug members, and a split clamping bushing mounted in the said tapered opening.

2. An electrical plug comprising two plug 90 members lying face to face, recesses for the electrical connections and having registering openings, an attaching piece having a tapered opening leading to said recess and provided with ears or lugs, extending between the plug members, and having apertures, screws extending through the apertures in the plug members and ears, and a split clamping bushing mounted in the said 95 tapered opening.

3. In an electrical attachment plug, the combination of a split plug body, an 100 interiorly coned ring with attachment plates which are secured between the body portions of the plug; binding posts and contact 105 springs within the plug; a twin lead passing

through the ring with its wires attached to said binding posts; and a bushing having its outer surface coned in correspondence to the inner surface of the ring while the inner surface of the bushing is roughened to take hold of the end of the lead the more tightly the more it is pulled from the plug.

In testimony whereof, I have hereunto signed my name at Philadelphia, Pennsylvania, this twentieth day of December, 1910. ¹⁰
WALTER C. FELLOWS.
